SIDE DISCHARGE GRATE FOR BATCH
SINTERING MACHINES

Walter Kelsey, New York, N. Y.

Application July 19, 1949, Serial No. 105,571

10 Claims. (Cl. 266—21)

1

This invention relates to a side discharge grate for batch sintering machines, in which the sinter cake is moved laterally from over the grate to be broken at a point distant from the grate.

One of the objections in the use of the grates as heretofore proposed was that the sinter would cake on the top of the grate bars and sometimes in the spaces between the bars, so that upon the attempted movement of the sinter cake in its frame laterally away from the grate, a resistance was encountered preventing a practical and workmanlike operation.

To overcome these and other objections, to the grates as heretofore proposed, the top of the improved grate is composed of bars placed on edge and spaced to give the required air passages, with the top edges as a whole fixed and aligned with the discharging motion of the sinter cake frame. This smooth top surface permits a sliding of the sinter cake, while in the frame, if there is no cohesion between the bars and the sinter. To remove such cohesion, the top of the bars, while held in a fixed place, are given a rocking motion to tilt their upper surfaces, in order to break any burned connection of the sinter cake to the grate, providing a shearing area or zone and doing this without moving the sinter cake. The grate bars are made in small abutting sections fitted and tied together in line forming groups running the width of the grate, these groups being assembled parallel with each other and properly spaced to cover the whole grate area.

Parts are mostly foundry made and any bar can be removed and replaced without disturbing other bars. The grate is designed to give a reasonable life and operation and can be installed at a reasonable cost. Thus, a fixed grate is provided on which materials can be sintered, this grate being operable to break the burned bond between the sinter cake and the top of the grate, enabling the sinter cake to be discharged or shoved from above the grate to one side of the grate, without difficulty.

The invention finds its embodiment in the combination of a plurality of spaced grate bars for supporting the sinter cake, each grate bar having a substantially flat top surface and a wedge shaped body converging to its narrower bottom surface, the vertical dimension of the bar being longer than the width of the flat top surface, with fixed oscillating centers, one for each grate bar and disposed near the top surface of the bars, and means for oscillating the lower end of the bars, whereby relatively large movements of

2

the bottom of the grate bars tilt the top surfaces of the grate bars a relatively small distance sufficient for separating the flat top surfaces of the grate bars from the bottom of the sinter cake by breaking the burnt connection.

The invention includes an improvement in the impervious strip between the grate and the walls surrounding the grate, which strip as improved is made up of abutting loosely attached individual members. The invention includes also a spacing strip at the top of the grate bars having circular contours spaced along its length in which portions of the grate bars having the same contour fit, being held by brackets and tie-rods. Also, 15 a link engaging the lower part of the notched grate bars, to oscillate the same for use. Also, in a heat compensating device, at one or two opposite sides of the grate, to allow for the expansion or contraction of the grate as a whole. 20 And finally, in a specific form of such compensating device.

The invention will be more fully described hereinafter, embodiments thereof shown in the drawings, and the invention will be finally pointed out in the claims.

In the accompanying drawings,
Figure 1 is a plan view of the improved grate;
Figure 2 is a vertical section on line 2—2 of Fig. 1;

30 Figure 3 is a vertical section on line 3—3 of Fig. 1;

Figure 4 is an enlarged sectional view of a few of the grate bars and the means for tilting the same, with a compensating spring device to allow for heat expansion and contraction;

35 Figure 5 is a section taken on line 5—5 of Fig. 4;
Figure 6 is a vertical plan view taken from line 6—6 of Fig. 4 showing the spring only;

Figure 7 is a broken side view of a grate bar 40 showing the bottom notches and rounded ends at the top;

Figure 7a is a top view of Fig. 7;
Figure 8 is a bottom view of Fig. 7, looking up;
Figure 9 is a vertical section of a grate bar taken on line 9—9 of Fig. 9a;

45 Figure 9a is a broken side view of Fig. 9;
Figure 10 is a vertical section of a grate bar having a rounded top taken on line 10—10 of Fig. 10a;

50 Figure 10a is a broken view of the end bar over which the impervious strip rests;

Figure 11 is a detail plan view of a tooth engaging link;

Figure 11a is a section on line 11a—11a of Fig. 11;

Figure 12 is a side view of the spacing and centering device for the grate bars;

Figure 12a is a section on line 12a-12a of Fig. 12;

Figure 13 is a broken plan view of the end impervious strip at the end of the grate;

Figure 14 is a vertical section on line 14-14 of Fig. 13;

Figure 15 is a vertical section on line 15-15 of Fig. 13;

Figure 16 is a vertical section on line 16-16 of Fig. 13;

Figure 17 is a broken plan view of another end impervious strip at the end of the grate;

Figure 18 is a vertical section on line 18-18 of Fig. 17;

Figure 19 is a plan view of the bed plate at one end of the grate on which the end impervious strips are disposed;

Figure 20 is a vertical section on line 20-20 of Fig. 19;

Figure 21 is a perspective view of the end impervious strip which rests on the bed plate;

Figure 22 is a sectional end view of the rear bed plate and rear impervious strip;

Figure 23 is a side view of Fig. 22;

Figure 24 is a sectional view of the front bed plate piece;

Figure 25 is a sectional view of the end bed plate piece;

Figure 26 is a plan view of an impervious piece of the front impervious strip tied to the front bed plate;

Figure 27 is a vertical section on line 27-27 of Fig. 26; and

Figure 28 is a side view of an alternate form of the compensating device, of Fig. 4, to allow for expansion and contraction of the grate.

Similar characters of reference indicate corresponding parts throughout the various views.

Referring to the drawings, the grate is shown in plan in Fig. 1 within the one piece sinter frame and in section in Figs. 2 and 3, with the sinter frame 59, 59A, 61 and 60, above the grate. The sinter charge is placed on the grate and held in place by the end walls 59 and 59A of a known construction, and between the front side wall 60 and the rear or back side wall 61 (Fig. 2). The walls 59, 59A, 60 and 61 are moved with the finished sinter cake from above the grate to a position away from the grate. After the sinter in the sinter frame has been completed, the frame may be moved completely away from the top of the grate, to a position where the sinter cake may be broken away from the frame, and thereafter the empty sinter frame is again placed over the grate. The sinter frame is then filled, and the contents are sintered. Generally, referring to Fig. 2, the sinter frame with its contents is moved horizontally from right to left of Fig. 2, until the end 60 is above the supporting wall 57. And thereafter, the empty frame is returned to the position shown in Fig. 2.

The grate bar unit is preferably wedge-shaped set on edge, wide edge up, and made short to minimize heat distortion. This wide bar top edge is smooth and straight without indentations on top or sides. A grate bar group runs the width of the grate between the impervious strips 42 and 41 (Fig. 2) and is composed of center pieces 35 and end pieces 36 and 36A. At the top of and above each joint of abutting ends or supports of the pieces 35, 36 and 36A, is a rectangular spacing strip 38 (Figs. 1, 2, 3, 4 and 5), set into the top of the grate bar and depressed below the level of

the top of the grate bar. This spacing strip 38 is toothed to fit the spacing of the grate bars and between and at the root of each tooth is a half circular space to fit the top of each grate bar at the end supports or over the center supports taking the top of two abutting and joined grate bars 35 and 36. The teeth on the spacing strips are shorter than the width of the top of the strip to prevent to some extent the fine sinter from getting under the teeth. These spacing strips 38 are made in workable lengths, butted together, and are held down in place by the rod ties 33 (Fig. 2), suitably placed connecting through the hole 38A (Figs. 5 and 12), and attached to brackets 33A on stationary supporting beams 55. These ties 33 span the oscillating T 50, (Fig. 2). This spacing strip 38 extends from end to end of the grate, one end abutting on the impervious piece 41 and the other end on the end-closing impervious pieces 39 or 40, held in place by springs 48 and 49 (Figs. 4 and 6). This spacing strip is fixed and holds each grate bar in a fixed position at the rocking center 38C (Figs. 4 and 12) of the semi-circular space between the teeth.

The lower part of each grate bar at an end or bearing rests on a T or bar 50 (Fig. 4, said lower part), and is held in a link 51 (Fig. 11) which oscillates with the bar 50 below the fixed point 38C giving the top of each grate bar at G (Fig. 4), a rocking and slightly oscillating or tilting motion in order to break the burned connection between the tops of the grate bars and the sinter cake without displacing or moving the sinter cake. This breaking of the burned connection between sinter cake and grate reduces greatly the power required to start the movement of the sinter cake in its frame. The said rocking motion of the grate bars is used only at the completion of the sintering and at the beginning of the discharge movement of the sinter frame. At other times, the grate bars are stationary.

Grate bar pieces 34 (Figs. 1 and 10), are the same as pieces 35 (Fig. 1), except that the top of central part of piece 34 is cut down to rounded top ends N and supports the end closing piece 39 (Fig. 1). The grate bar pieces 37 and 37A (Fig. 1), are the same as pieces 36 and 36A (Fig. 1), except that the top of the central part of each piece is cut down to the rounded ends N and to take the end closing pieces 40 (Figs. 1 and 4).

The space from the top of each grate bar to the top of the supporting bar 50 is the same for all bars, except those with the rounded tops, giving, with the grate bars in vertical position, a level grate surface. Each group of grate bars is assembled with the surface H (Fig. 9a) of pieces 36 in contact with the impervious spacing bar 42 attached to the bed plate pieces 45 (Fig. 2). The pull of the sliding sinter cake longitudinally aligned with the grate bars will keep the groups of bars in position.

The temperature of the gases passing through the grate will vary greatly and allowance is made for the expansion and contraction of parts of the grate or the grate as a whole. With the spacing strip 38 abutting against the fixed impervious piece 41, allowance is made at the opposite nominally fixed end of the grate for any expansion. This nominally fixed end of the spacing strip contacts with the impervious piece 40 (Fig. 4) which rests on the bearing plate piece 44, (Figs. 3 and 4). With a short grate, as shown in these drawings, a single spring, as 48 (Fig. 6), can be made to take up all the motion and hold all the bars in the desired approximately up-

right position. One end of the spring is fixed and one end is movable, the movable end being secured to the piece 40. The supporting member 50 is also affected by the heat. To minimize distortion due to heat in this piece 50, it can be made in short sections connected together end-to-end by flexible joints (not shown). A roller bearing 54 is to be placed at each end of each short section so that uneven loading on the grate will not displace any part of the grate.

The roller bearings, not shown, are in the bearing housing 54 which is shown only as the enclosure housing and the designation mark 54 is herein used to include the roller feature. (Fig. 3.)

In the short grate, as here shown, the operating shaft 52 (Fig. 3), is placed at the end opposite the end having the spring 48. The action of the supporting member 50 from the application of the heat will be about the same as the action on the spacing strip 38. Piece 50 is held at the operating shaft 52 and the other end is free. With a long grate, the operating shaft 52 would be placed near the center with the supporting member 50 held at the shaft with both ends free. In this case, springs would be used at each end, the light spring 48 (Fig. 6), restrained by a tie 48A (Fig. 4), to keep the bars vertical and centered. As expansion increases, a heavier spring 49 (Fig. 6), restrained by tie 49A (Fig. 4), will come into action to keep the bars vertical and centered. A third, still heavier restrained spring may be used if necessary. This spring location at the underside of the grate is convenient. In case the hot gases act unfavorably on the springs, they can be replaced by weights or springs away from the gases and the action conveyed to the restraining piece 40 by suitable linkage.

A linkage for holding the spacing strips 38 in place by its action through the restraining piece 40 is shown in Fig. 28. The lever 66 is pivoted at 69 on the support 71 and acts on the restraining piece 40 at the lever end 70. The weight on line 62 is divided by the adjusting lever 63 part of the weight tieing directly by tie 65 to restraining piece 40 to hold that piece in place and part tieing by tie 64 to the point 67 placing that part of the weight so as to act on the lever 66. This latter part of the weight brings the required pressure on the restraining piece 40 at lever end 70. The action of the expanding spacing strip 38 is to move the lever end 70 against this pressure and raise the other weighted lever end at 67 along the arc 68 with pivot 69 as a center. This motion increases the effective lever arm between point 69 and point 67 and increases the pressure exerted by lever end 70 on the restraining piece 40. With identical weights and levers at each end of a grate and the spacing strip free to move as it expands by heat, the spacing strip will be held central under all heat conditions as the pressure at each end will be equal. Friction will be the only disturbing element in this combined and opposing lever action and that can be kept at a minimum.

The grate bars extending from side to side of the grate are also affected by the heat. The end bars 36 will rest against the bolted down impervious spacing bars 42 (Fig. 2) with an opening allowing for expansion made at the opposite or front end. This opening is covered by impervious spacer pieces 47 (Fig. 2). This spacer piece 47 (Figs. 2, 26 and 27), is bolted down and held in place by hooks K engaging the

short sections of bearing bars M (Fig. 24), which are part of a bed plate 46 (Fig. 2). The expansion of the parts of group of grate bars is allowed for by the sliding lengthwise of the rollers in the bearings 54 under the pieces 50.

The oscillating piece or T 50 rests on roller bearings 54 (Fig. 2) (indicated by housing only), which are supported on the grate supporting beams 55. The operating shaft 52 (Fig. 3) is connected through suitable arm and bearing 53 (indicated only). This shaft is supported by bearings (not shown) and given a rotary reciprocating motion through power connections (not shown).

This grate is surrounded by four bed plates 43 and 44 (Fig. 3), and 45 and 46 (Fig. 2). The two end walls 59 and 59A and the front wall 60 and rear wall 61 constituting the sinter frame are supported on these bed plates. Wall 61 is directly on a bed plate, and the other walls (60, 59 and 59A) rest on bearing bar M and bearing plates 43A and 44A. The walls 59 and 59A have wearing plates 59B secured thereto. The bearing bar M is secured to the bed plate 46; and the bearing plates 43A and 44A are secured to their respective bed plates. These bed plates are anchored in place on the structure or foundation, anchor bolts and grout holes not being shown. Bolting for the impervious pieces 41 and 42 are not shown. A bolt hole 32 for the holding down bolts for piece 47 is shown. Bed plate 43, with impervious piece 41, is used at one end of a short grate with the operating shaft 52 located at the same end. At the opposite end of a short grate, bed plate 44 (Figs. 3 and 4) is provided, to which one end of a compensating spring is secured, with the other end of the spring movable with the piece 40. The operating shaft 52 is placed at the center of a long grate and compensating devices are placed at both ends. Pieces 39 and 40 are placed end-to-end and locked at 0 against any end uplift. (Figs. 13 and 17.)

The inner edge of each impervious strip in contact with the grate will be subjected to the full application and temperature fluctuation of the heated gases, and this heat action would soon distort and break the castings if the impervious edges were made in one piece with the several bed plates. To avoid this, the inner edge of or the whole of these impervious strips are made of short sections or pieces so loosely attached to the bed plates that distortion, due to heat, will not be carried back into the bed plates. These pieces are 41 (Fig. 21) connected to bed plate 43 (Fig. 3), 39 and 40 connected but free to slide on bed plate 44 (Figs. 3 and 4), 42 connected to bed plate 45 (Fig. 2), and piece 47. Pieces 47 are held down by bolts (not shown), passing through the openings 32 in the pieces 47 and through the openings 32A of the bed plate 46 (Figs. 24, 26 and 27).

I wish it to be understood that I do not desire to be limited to the exact details of construction shown and described, for obvious modifications will occur to a person skilled in the art.

I claim:

1. In a side discharge grate for a batch sintering machine having a grate with four sides and a sinter frame over the grate having walls 70 surrounding the grate, the combination of an impervious strip along each of the four sides of the grate, between each side of the grate and the adjacent surrounding wall of the sinter frame, said grate being composed of groups of grate bars abutting end to end and extending

over the whole surface included between the said impervious strips, the tops of the said grate bars being horizontal and level, and the tops of the said impervious strips being level with the tops of the said grate bars.

2. In a side discharge grate for a batch sintering machine, the combination of a sinter frame, a grate, said grate being composed of groups of grate bars abutting end to end and extending between each side of the grate space, parallel rows of groups of such grate bars extending the length of the grate space, the top of each of the grate bars being horizontal and free to tilt, oscillating centers for said grate bars spaced and held in fixed places, toothed spacing strips for spacing the centers of oscillation, means for supporting the grate bars, means on said supporting means engaging the bottom of the said grate bars, and means for oscillating the said grate bar supporting means.

3. The structure of claim 2, including the combination of a toothed spacing strip having spaced teeth, the space between two teeth being semicircular, said teeth having a narrowed extension of a thickness less than at the semicircular part, the length of the tooth being less than the width of the spacing strip, and grate bars having ends abutting each other, said spacing strip fitting over the abutting and terminal ends of grate bars with said grate bar ends being fitted to the semicircular parts of the said spacing strip with the top of the said spacing strip when assembled with the grate bars below the level of the top of the grate bars.

4. The structure of claim 2, including the combination of a grate bar supporting bar, an elongated link on the top of and attached to said supporting bar, the long link axis extending across said supporting bar providing spaces at each side of the bar, and a grate bar having notches, said notches being engaged by the link, and the projection between the notches being within the link, said grate bar being formed of abutting members each of which has a projection, the link holding the abutting members together.

5. The structure of claim 2, including a supporting beam parallel with the spacing strip, a

bracket on the beam, and means connecting the spacing strip to the bracket.

6. The structure of claim 2, including the combination of a plurality of supporting beams, brackets attached to the supporting beams engaging the beams, and tie rods connecting the brackets and the spacing strips, said brackets and tie rods being located and spaced at suitable intervals.

10 7. The structure of claim 2, including the combination of a movable member at one end of the same normally pressing against said spacing strip, and a movable pressure means acting on said movable member to permit the expansion and contraction of said spacing strip.

15 8. The structure of claim 2, including a plurality of oscillating supports, the top of said grate bars being held in fixed position by said toothed spacing strips, means for holding said strips, said means including a weight operated lever, and an arm on said lever exerting a pressure on the strips, the weight carrying arm of said lever being so placed that with any motion of the lever by said strips, the effective length of the weight arm will be changed.

20 9. The structure of claim 2, including the combination of an impervious strip along each of the sides of the grate, said impervious strip being composed of a plurality of separate pieces abutting end and end and individually replaceable, and bed plates for supporting said pieces.

25 10. The structure of claim 2, in which the oscillating means support the entire weight of the grate bars.

35 WALTER KELSEY.
